UNITED STATES PATENT OFFICE.

GEORGE SCHRADE, OF NEW YORK, N. Y.

FEEDING MECHANISM FOR SEWING-MACHINES.

SPECIFICATION forming part of Letters Patent No. 487,079, dated November 29, 1892.

Application filed May 8, 1891. Serial No. 392,119. (No model.)

To all whom it may concern:

Be it known that I, GEORGE SCHRADE, a citizen of the United States, and a resident of the city, county, and State of New York, 5 have invented a new and useful Improvement in Sewing-Machines, of which the following is a specification.

The object of this invention is to so arrange the mechanical movements of a sewing-machine that a high rate of speed and durability may be obtained.

The invention consists in the construction and combination of parts of the machine, as will be hereinafter more particularly set forth, 15 reference being had to the accompanying drawings, in which—

Figure 1 represents a side view of my improved machine. Fig. 2 is a front end view of Fig. 1. Fig. 3 is a longitudinal sectional view of Fig. 1, showing the needle-bar, its guide, and means to operate it, and also the side view of the intermittent feed mechanism. Fig. 4 is a side view of the revolving feed-arbors and the connecting-gears. Fig. 5 is a 25 side view of the internal feed-gear. Fig. 6 represents the side view of the star-wheel for operating the internal gear. Fig. 7 represents the star-wheel in position to move the internal gear. Fig. 8 is an end view of the 30 needle-bar and a side view of the needle-bar eccentric. Fig. 9 is a cross-sectional view of the star-wheel. Fig. 10 is a cross-sectional view of the internal gear and feed-roll driving-gear. Fig. 11 represents a top view of 35 the feed-arbor and its bearings, the intermediate gears, intermittent feed-gears, the automatic needle-stripper lever, and feed-arbor lifter. Fig. 12 is an end view of the feed-arbors, the side view of the top feed-arbor support, means to raise and lower the feed-roll and needle-stripper. Fig. 13 is the side view of the intermediate gear-support. Fig. 14 is a sectional view of the intermediate gears, gear-support, and means to secure the support. Fig. 15 shows the end view of the 45 adjustable feed. Fig. 16 is a top view of Fig. 15. Fig. 17 shows the inclined slot to guide the adjustable feed, and Fig. 18 represents the end view of the gang-gear spline. 50 A in the several drawings represents the frame for supporting the various parts composing the machine.

A' is a cloth-plate for supporting the material to be sewed.

A² is a revolving arbor driven by the grooved 55 pulley A³ (shown in Fig. 1) and imparts motion to the several working parts of the machine.

A⁴ represents a spool of thread held in place by the thumb-screw A⁵. The thread 60 receives the proper tension as it passes through the tension-disks A⁷, which are regulated by the thumb-nut A⁸.

B, Figs. 1, 2, and 3, is a bracket secured to the frame A by screws b b, and supports the 65 vertical needle-bar rod B', which is made tapering at its lower end, as shown at b', Fig. 3, that it may always find a firm central bearing, and is held in place by the set-nut B².

C, Figs. 1, 2, 3, and 8, is a vertically-reciprocating needle-bar forming an overhanging arm. By passing the material under the needle at the outer end of this arm with the edges closer to or farther away from the frame A of the machine the operator is enabled to sew 75 at a greater or less distance from the edge of the material. The needle-bar C has a central passage through which the rod B' passes, as shown at C⁹, Fig. 3. This passage has a manifold purpose. It lightens the bar, thereby lessening the liability to wear, is easily 80 and cheaply made, and forms a perfect wall for the guide-rod B'.

C⁵, Figs. 3 and 8, is a stud forming part of the needle-bar, to which the eccentric-rod C⁶ 85 is secured.

C⁷ is the eccentric-rod strap surrounding the eccentric C⁸, which is driven by the arbor A².

The needle-bar C is guided vertically up 90 and down on the rod B', while the sides c of the bar, bearing against the walls of slot C⁴, as shown in Fig. 3, prevent a swinging or side motion.

C' is a needle-clamp nut by which the needle C³ is held in the clamp C².

D and D' in the several drawings represent arbors having the enlarged parts d, as shown in Figs. 1, 2, and 4, between which the material to be sewed is intermittently fed forward. 100 The arbor D', as shown in Fig. 4, is stationary, except as to its revolution, while the arbor D is supported at one end of a pivoted lever, as represented in Figs. 4, 11, and 12, which

permits of its being raised when it is desired to put in or remove the work.

D^2 in Figs. 4 and 11 is a gear by which the arbor D is driven by intermediate gears from 5 the main arbor A^2 .

D^3 and D^4 are gears of the same number of teeth and diameter, which makes the arbor D and D' turn in opposite directions or inwardly, causing the material to be sewed, to 10 receive the same pressure and movement on both sides, thereby preventing any undue strain on one piece more than another, which is invariably the case in the well-known drop or wheel feed.

15 I in Figs. 4, 11, and 12 is a pivoted lever secured to the lug I^2 , Fig. 11, by aid of the screw I^3 and forms a journal for the arbor D. This adjustable or swinging journal is essential, as it allows the arbor D to be raised 20 while the material to be sewed is placed between or removed from between the enlarged parts d of the arbors D and D' . The adjustment is also necessary to the feeding of the goods over seams and different thicknesses of 25 goods. The slot D^5 in the frame A, Fig. 4, permits the arbor D to be raised.

D^7 , Figs. 1, 2, 11, and 12, is the lifter of arbor D and is secured to the arbor D^8 , which is provided with the eccentric D^9 , as shown in 30 Figs. 11 and 12. By turning the lever D^7 the higher part of the eccentric D^9 is forced against the top of the lever I, as shown in Fig. 12, moving it downward and separating the rolls D and D' .

35 I^5 , Figs. 11 and 12, is a lug for retaining the tension or pressure spring I^{11} in place.

I^{10} is a screw for adjusting the spring I^{11} , that more or less pressure may be given to the arbor D against the arbor D' . The spring 40 I^{11} also forms a yielding pressure, permitting various thicknesses of material to readily pass through between the enlargements d of the arbors D and D' .

N, Fig. 2, is a stripper held to the frame A 45 by the screw N^2 and provided with the recess N^3 at its upper end; also, it has a right-angle flange N' , through which the needle passes, and prevents the cloth from being raised or drawn up when the needle rises to permit the 50 material to be fed forward.

I^6 is a lever secured to the frame A at I^7 and is provided with the screw I^8 , as shown in Figs. 11 and 12. This screw I^8 passes through the slot I^9 of the frame A, as represented in Figs. 2 and 11, entering the hole N^3 of the stripper N, as shown in Fig. 2.

I^4 , Figs. 11 and 12, is an arm secured to the lever I and comes in contact with the lower sides of the lever I^6 , raising its free end, and 60 the screw I^8 , which, being connected with the stripper N, raises and lowers it simultaneously whenever the journaled arbor D is raised or lowered by the pivoted lever I. Thus it will be seen that the stripper N and 65 arbor D are both operated together at the discretion of the operator. Whenever it is desirable not to have the stripper operate with

the arbor D, the screw I^8 is turned in so it does not come in contact with the stripper.

E in the various drawings represents an internal gear, which is loosely mounted on the revolving arbor A^2 , as shown in Fig. 3, and has a fixed gear E^2 , secured to the internal gear-hub E^3 .

H and H' are intermediate gears secured 7 to each other and running loosely on the stationary arbor H^2 , as shown in Figs. 11 and 14. These gears H and H' are intermittently moved by the gear E^2 and operate the arbor D through the medium of the gear D^2 , as represented in Fig. 11.

H^3 , Figs. 11, 13, and 14, is an adjustable block having arbor H^2 and tenon H^5 , which is made to adjust in the mortise H^6 of the frame A. (Shown in sections in Fig. 14.) The block 85 H^3 is made adjustable in the mortise H^6 that various sizes of the intermediate gears H and H' may be used to increase or lessen the speed of the arbor D.

F, Figs. 3, 6, 7, and 9, represents a star-wheel 9c having teeth F' and pivot-slot F^2 , as shown in side view, Figs. 6 and 7.

G, Figs. 3, 6, 7, and 9, is an eccentric secured to the driving-arbor A^2 and eccentrically operating the pivoted star-wheel F 95 within the internal gear E.

F^3 is a pivot-support secured to the frame A by screw F^4 and having a pivot F^5 , which enters the slot F^2 , as shown in Figs. 3, 6, and 7. This pivot or post prevents the star-wheel 10 F from being carried around with the eccentric and is the direct means of producing the intermittent action of the internal gear E, as shown in Fig. 7.

The eccentric G, as shown in Fig. 7, is represented as swinging the top of the star-wheel over in the direction of the arrow, and as its teeth mesh into those of the upper part of the internal gear the highest part of the eccentric G is opposite the slot F^2 , at which time the teeth 11 of the star-wheel move substantially in a vertical or downward line, which action is caused by the pivot F^5 holding the star-wheel, when the internal gear ceases to move a sufficient time to allow the needle to descend and be 12 drawn out of the material. Should all the teeth of the star-wheel be removed and a lever formed, as represented by the dotted lines O in Fig. 7, the same result would be obtained, as the end O' of the lever by the action of the 13 eccentric G and pivot F^5 is moved at the top of the star-wheel in the form of an ellipse. When it advances upward, it engages a tooth of the internal gear E, moves it forward, withdraws, and, returning, engages the next tooth; but the star-wheel F is preferable, as its teeth never leave those of the internal gear E, which avoids all liability of a blow or noise, the several points of contact making it more durable and positive.

To avoid the inconvenience of removing the intermediate gears that a longer or shorter stitch may be made and the action of the arbors D and D' be varied, I show a modifica-

tion in Figs. 15, 16, and 17, which permits a ready change. On the flange of the internal gear E a worm-thread is formed, as at V, Fig. 16, this worm engaging with the gears, mounted on the shaft K, drives the arbor D' through the bevel-gears J⁵ and D² the same as the intermediate gears H and H'. The arbor K has a spline-groove K', in which the spline J² fits. The spline prevents the gang-gears 1, 2, 3, 4, 5, and 6 from turning, but allows a free longitudinal adjustment that any desired gear of the gang may be readily engaged with the worm V. This I accomplish by adjusting the spline-head J' at various points in the slot J⁴ of the frame A, as shown in Fig. 17, and securing it in place. The strap J⁶ forms a journal for arbors D' and k and permits the elevation of the arbor K that different gears in the gang may be set over the worm V. When a longer or shorter stitch is required, the spline-head J' is set at any of the scales indicated by the figures 1, 2, 3, 4, 5, and 6, which gives the exact length of the stitch desired.

I do not limit this feed mechanism to chain-stitch machines, but will adapt it to shuttle machines as well.

Having thus fully described my invention, what I claim as new, and desire to secure by Letters Patent of the United States, is—

1. In a sewing-machine, the combination, with a rotary arbor, of an internal gear-wheel mounted loosely thereon and adapted to be intermittently operated, mechanism for operatively connecting the arbor and the wheel, and a feeding device connected with and adapted to be operated by said gear-wheel, substantially as set forth.

2. In a sewing-machine, the combination of an arbor provided with a fixed eccentric, an internal gear mounted loosely on said arbor, an intermittent actuating device on the eccentric adapted to engage with the internal gear, a stop for engaging with the actuating device to prevent its rotation with the eccentric, and a feeding device connected with and adapted to be intermittently operated by said internal gear, substantially as set forth.

3. In a sewing-machine, the combination of an arbor provided with an eccentric, an internal gear-wheel loosely mounted on said arbor, a star-wheel on the eccentric engaging with the internal gear, a stationary stud engaging the said star-wheel, and feeding mechanism connected with and adapted to be intermittently operated by said internal gear-wheel, substantially as set forth.

4. In a sewing-machine provided with an intermittently-movable gear-wheel, the combination, with the feed-rolls, the shaft of one

of which is provided with a gear-wheel, of a block adjustably secured to the frame of the machine, interchangeable gear-wheels mounted on the block and adapted to engage with the intermittently-movable gear-wheel and with the gear-wheel of one of the feed-rolls, substantially as set forth.

5. In a sewing-machine, the frame of which is provided with a mortise, the combination, with the feed-rolls, the shaft of one of which is provided with a gear-wheel, of an intermittently-movable gear-wheel, a block provided with a tenon adjustably secured in said mortise, and interchangeable gear-wheels mounted on said block and adapted to engage with the intermittently-movable gear-wheel and with the gear-wheel of the shaft of one of the feed-rolls, substantially as set forth.

6. In a sewing-machine, the combination, with a lever pivotally secured to the frame, of an intermittently-operated feed-roll journaled in one end of the lever, a supplemental feed-roll, an adjustable pressure-regulator connected with the said journal, and a cam engaging with the other end of the lever, substantially as set forth.

7. In a sewing-machine, the combination, with the upper and lower feed-rolls, one of which is movable toward and from the other one, of a needle-stripper and mechanism engaging with the needle-stripper and with the movable feed-roll, whereby the needle-stripper is raised simultaneously with the separation of the rolls, substantially as set forth.

8. In a sewing-machine, the combination, with the feed-rolls, of a lever, a needle-stripper detachably connected therewith, a second lever engaging with the shaft of one of the feed-rolls, and means for detachably connecting said lever, substantially as set forth.

9. In a sewing-machine, the combination, with the lever pivotally secured to the frame and having a laterally-projecting arm near one end, of feed-rollers, the shaft of one of which is journaled in the end of said lever, means for operating the lever, a second lever pivotally secured to the frame and adapted to be engaged by said arm, and a needle-stripper detachably secured to said second lever, substantially as set forth.

In testimony that I claim the foregoing as my invention I have signed my name, in presence of two witnesses, this 20th day of April, 1891.

GEORGE SCHRADE.
